DESIGN FOR A BRACELET

Suzanne Ray-Dupuis, New York, N. Y., assignor to Raybert Products Corp., New York, N. Y., a corporation of Delaware

Application November 7, 1946, Serial No. 134,597

Term of patent 3½ years

(Cl. D45—4)

To all whom it may concern:

Be it known that I, Suzanne Ray-Dupuis, a citizen of France and resident of New York, county and State of New York, have invented a new, original, and ornamental Design for a Bracelet, of which the following is a specification, reference being had to the accompanying drawing, forming a part thereof, in which:

Fig. 1 is a front view of a bracelet embodying

my design, showing one of the pivotal arms thereof in open position;

Fig. 2 is a side view of the bracelet, with both pivotal arms in closed position; and

Fig. 3 is an end view of the bracelet as shown in Fig. 2.

I claim:

The ornamental design for a bracelet, as shown.
S. RAY-DUPUIS.
